DESIGN.

E. H. BENNETT.
RUG.

No. 21,004.

Patented Aug. 18, 1891.

UNITED STATES PATENT OFFICE.

ERNEST H. BENNETT, OF EAST ORANGE, NEW JERSEY, ASSIGNOR TO JOHN BROMLEY & SONS.

DESIGN FOR A RUG.

SPECIFICATION forming part of Design No. 21,004, dated August 18, 1891.

Application filed February 2, 1891. Serial No. 379,922. Term of patent 3½ years.

To all whom it may concern:

Be it known that I, ERNEST H. BENNETT, a citizen of the United States of America, residing at East Orange, in the county of Essex and State of New Jersey, have invented a certain new and original Design for a Rug, of which the following is a specification, reference being had therein to the accompanying drawing.

10 My invention relates to the surface ornamentation of rugs; and it consists of the design therefor, which is fully illustrated in the accompanying photographic drawing, its leading features being the ornamentation around the 15 edges constituting the border and an ornamental floral design in the field center.

I claim as my invention—

1. The design for a rug, substantially as shown and set forth.
2. The design for the border of a rug, substantially as shown and set forth.
3. The design for the ornamentation of the field center of a rug, substantially as shown and set forth.

In testimony whereof I affix my signature in presence of two witnesses.

ERNEST H. BENNETT.
